UNITED STATES PATENT OFFICE.

DÉSIRÉ VANDE GENACHTÉ, OF NEW YORK, N. Y.

DESIGN FOR A LAMP SHADE.

Application filed January 24, 1928. Serial No. 25,016. Term of patent 7 years.

To all whom it may concern:

Be it known that I, DÉSIRÉ VANDE GENACHTÉ, a subject of the King of Belgium, and a resident of the city of New York, borough of Manhattan, in the county of New York and State of New York, have invented a new, original, and ornamental Design for a Lamp Shade, of which the following is a specification.

Reference is had to the accompanying drawing, wherein

I claim—

The ornamental design for a lamp shade as shown.

Signed at New York, in the county of N. Y. and State of N. Y. this 20th day of Jan. A. D. Nineteen hundred and twenty-eight.

DÉSIRÉ VANDE GENACHTÉ.
